CLAIM

The ornamental design for a multiple beam antenna, as shown and described.

DESCRIPTION

FIG. 1 is a perspective view of a multiple beam antenna showing our new design;

FIG. 2 is a side elevational view thereof;

FIG. 3 is a top plan view thereof; and,

FIG. 4 is a bottom plan view thereof.

The pole (FIGS. 1, 2 and 4) and pole mounting (FIG. 4) are shown in broken lines for illustrative purposes only and form no part of the claimed design.
